CLAIM

The ornamental design for a ball launching device, as shown and described.

DESCRIPTION

FIG. 1 is a perspective view of a ball launching device of the present invention.

FIG. 2 is a side view of a ball launching device of FIG. 1. The opposite side of the device is a mirror image of FIG. 2. FIG. 3 is a top view of a ball launching device of FIG. 1. FIG. 4 is a bottom view of a ball launching device of FIG. 1.

FIG. 5 is a rear view of a ball launching device of FIG. 1; and,

FIG. 6 is a front view of a ball launching device of FIG. 1. The broken lines shown in the drawings depict portions of the ball launching device that form no part of the claimed design.
